**DAY AND NIGHT DISTINGUISHING CLOCK
CONTROLLED SWITCH**

Raymond D. Smith, 955 Main St., Easton, Conn.

Filed Feb. 13, 1956, Ser. No. 564,905

11 Claims. (Cl. 200—38)

This invention relates to time telling instruments or chronometers and particularly to clockwork operatively combined with, or incorporated within, a clock controlled electric circuit controlling unit or time switch such as includes circuit making-and-breaking mechanism operating automatically at selectively settable times of day or night.

A time switch of this nature is proposed in my U.S. patent, Reissue No. 23,783, wherein the electric circuit controlling unit may comprise a traveling, contact-activating element driven by clockwork to revolve constantly at a speed of one revolution in 24 hours. In the time switch of said patent there is a conventional 12-hour clock face swept by clock hands rotating about an axis for telling time in conventional manner and in addition there is a stationary circular 24-hour scale of time indicia concentric with the clock face and separately settable indicators that are selectively turnable to various stations on the circle in register with the 24-hour scale. Such indicators in the time switch of the patent are operatively associated with clockwork controlled switch operating mechanism for automatically switching a load circuit at predetermined times which constantly remain displayed by the position of the settable indicators as stationed in register with the 24-hour scale.

But in the time switch of the aforesaid patent there is need for, and not present, some visible signal means by which to know whether the telling of time displayed in usual manner by the angular position of the conventional clock hands is "time of day" or whether it is "time of night," since one revolution of the hour hand of the clock takes place during the day and the next revolution takes place during the night. An example of such need is when the clock has been thrown "off time" by a period of inaction. On putting the time switch back into use in such circumstances the clock hands must not only be set at the correct time telling position on the clock face but the position on the aforesaid clock driven electric contact-activating element in its circle of travel relative to the 24-hour scale must be known inasmuch as such element can have two diametrically opposite positions corresponding to any single position of the hour hand. This is because the hour hand makes two revolutions while the clock driven electric contact-activating element is making only one revolution. In the aforesaid patent this condition of proper synchronism between traveling contact-activating element and 24-hour scale for setting the times for automatic switch action can not be ascertained by merely viewing externally visible parts of the time switch because the contact-activating element is concealed within the switch mechanism by opaqueness of the aforesaid time setting indicators.

The present invention solves this problem and enables the user at all times to know, merely by observing externally visible parts of the time switch, whether the clock hands are telling "time of day" or "time of night" and whether the contact activating element is in proper syn-

2

chronism with the sectional 12-hour, day-and-night markings on the 24-hour scale.

Successful embodiments of the invention are set forth in the following description having reference to the accompanying drawing, wherein certain parts are lined for the colors red and black.

Fig. 1 shows in front view a time indicating electric circuit controlling device embodying one form of the invention in which the clock hands point to "time-of-day," and in which it can be known by newly provided signal means that an internally concealed clock driven electric contact-activating element is synchronized in proper relation to a 24-hour scale having 12-hour day-and-night sections.

Fig. 2 is a similar view in which the clock hands are in similar angular positions but known by observation of the signalling means to be telling "time-of-night" instead of "time-of-day."

Figs. 3 and 4 show a different setting of the contrasting color bands which display the day and/or night time periods during which the clock controlled switch will remain respectively open or closed.

Fig. 5 shows a setting of the color bands that indicates a condition of the time switch whereby the load current will remain always off and never become automatically switched on.

Fig. 6 shows a setting of the color bands that indicates a condition of the time switch whereby the load current will always remain on and never become automatically switched off.

Fig. 7 on an enlarged scale is a view taken partially in section on the plane 7—7 in Fig. 1 looking in the direction of the arrows.

Fig. 7a is a fragmentary view of a modified form of the signal giving parts of Fig. 7.

Fig. 8 is an exploded fragmentary perspective view of the clock face, the day-or-night indicating signal and the clock hands.

Figs. 9 and 10 are enlarged views of the indicator setting spindles taken respectively on the planes 9—9 and 10—10 in Fig. 1 looking in the direction of the arrows.

Figs. 11, 12 and 13 are views taken in section on the planes 11—11, 12—12 and 13—13 respectively, in Fig. 7, looking in the direction of the arrows.

Fig. 14 shows a modified relationship of the clock face and the 24-hour dial wherein the latter forms a ring encompassing the former.

Since the general character of the basic operating parts of the clock and time switch mechanism is so similar to that disclosed in my U.S. Patent No. Re. 23,783, the corresponding parts of the present time switch need be described only briefly.

The framework includes a front frame plate 20 having a large circular aperture in which is journaled a bearing ring 28 of insulating material projecting somewhat both forward and to the rear of plate 20 so as to carry on respectively opposite sides of the latter coaxially rotatable ring gears 10 and 11. These gears are alike except that gear 10 is fast to ring 28 while gear 11 can rotate relatively thereto. By means of an internal keyway in ring 28, that is receptive to a rearwardly bent ear 27' on a white indicator disc 27, the turning of ring gear 10 turns disc 27 and stations it in selective rotary positions. By means of a pin 61 projecting forward from ring gear 11 and which engages a hole in a radial extension 26' of a red indicator disc 26, the turning of ring gear 11 turns disc 26, and relatively to disc 27 if desired. Thus each of discs 26 and 27 can be stationed independently of the other in selective rotary positions about a hollow stationary main bearing post 15 which supports them and which is fixedly mounted in an aperture in an inter-

mediate frame plate 21 of insulative material. Post 15 at its front end supports a clock dial 34.

Ring gear 10 is turned by means of a meshing pinion 13 that is caused to rotate in unison with its spindle 40 by means of a spline 70 which as shown in Fig. 10 permits spindle 40 to slide axially in relation to pinion 13. Spindle 40 is equipped with a handle knob 40' accessible outside of housing 25. Pinion 13 carries a guard flange 42 that overlaps the front face of ring gear 10. Gear 11 is turned by a similar meshing pinion 12 that is caused to rotate in unison with its spindle 39 by means of a spline 70 which as shown in Fig. 9 permits spindle 39 to slide axially in relation to pinion 12. Pinion 12 carries a guard flange 41 that overlaps the rear face of hub ring 28. Spindle 39 is equipped with a handle knob 39' accessible outside of housing 25. Other but stationary guard flanges maintain ring gears 10 and 11 close to front frame plate 20 two such flanges comprising depending portions of a clip-like retainer 46 that straddles the top edge of plate 20 and is secured thereto by the spacer posts 23. Retrogressive or clockwise turning of the ring gears 10 and 11 is limited to a small extent by two leaf spring clicks 47 that engage with the teeth of both ring gears in a manner freely to permit rotary setting of the indicator discs 26 and 27 in only a counter clockwise direction. Clicks 47 are extensions of another clip-shaped member of resilient sheet metal that straddles the bottom edge of frame plate 20 and is secured thereto by spacer posts 23.

The turning of each of spindles 39 and 40 is frictionally opposed by means of a "live" brake cone 38 which is fixed on the spindle by a set screw 43 and rubs rotatively against a "dead" brake cone 37 that is fixedly mounted in frame plate 20 and affords rotary bearing for the spindle 39 or 40 which extends through it. The mutually engaged smooth friction affording conical surfaces of each set of brake cones 38 and 37 are kept constantly pressed together by the axially exerted tension of a cupped spring washer 44 whose force of axially exerted tension is adjustably maintained by thrust determining nuts 52 both having threaded engagement with the spindle 39 or 40.

The function of the brake cones is to hold each of the indicator discs 26 and 27 stationary against any tendency toward rotary displacement caused by turning of the other disc. Such tendency arises from the fact that the discs are radially split and helically interleaved with each other as described in my reissue Patent No. Re. 23,783. In other words, each disc overlaps and extends through a split portion of the other disc and is mounted to be turnable relatively thereto and relatively to a scale 68 of time designating indicia. The rear face of disc 27 whose front face is, say, white is continuously conductive and the rear face of disc 26 whose front face is a contrasting color such as red is continuously insulative at such common radius of curvature as provides a continuous circular commutative track composed of exposed component rear surfaces of said discs that are wiped continually by the tip of a clockwork driven revolving contact element 29. The whole, or any arcuate extent, of such circular commutative track can be composed of conductive or insulative components by the manual setting of the discs 26, 27 in selective circular relation to each other as well as in relation to the frame plate 20. Relative movement of the interleaved discs in one rotary direction is limited by abutment of the ear 27' on white disc 27 against the radial extension 26' of red disc 26 to a relative position of the discs wherein the said commutative track is insulative around the complete circle at the rear surfaces of the discs in the setting shown in Fig. 5, while relative movement between these same discs in the opposite rotary direction is limited by abutment of a stud 71 on white disc 27 against the dead end of an arcuate notch 72 in red disc 26 to a relative position of the

discs wherein the said commutative track is conductive around the complete circle at the rear surfaces of the discs in the setting shown in Fig. 6.

As best shown in Figs. 7 and 12 the wiping contact element comprises a forwardly inclined resilient finger 29 preferably of leaf bronze branching from a round band 73 of the same sheet material that is ringed about and fixedly mounted on the insulative hub 14 of a gear 8 of insulative material. Gear 8 rotates freely on a shouldered portion of the aforesaid hollow stationary main bearing post 15.

Clock dial 34 bearing the hour graduations 45 is fixedly stationed on post 15 by the head flange of an externally threaded bushing 35 which bushing engages internal threads in the front end of the post. At least the rear surface of clock dial 34 is insulative and serves axially to retain the interleaved signal discs 26 and 27 in their swivelling relation on the bearing post 15. The discs are constantly pressed forward against a conductive washer 69 clamped between the front end of post 15 and clock dial 34. The axial expansion of a spring coil 60 exerts thrust between a conductive washer 59 stationed against the shoulder on post 15 and the flange of an axially slidable conductive sleeve 67 that is constantly thrust forward against the discs 26 and 27 by spring 60. The front colored faces of discs 26 and 27 are constantly visible fully or in part through an annular space about the clock dial 34 between the latter and a stationary mat ring 62 carrying a circuitous 24-hour scale 68 of time indicia.

In the time switch of my aforesaid patent there were journaled inside of a main bearing post, comparable to post 15, a hollow shaft such as 16 for the hour hand 31, and inside of such hour hand shaft a spindle 17 for the minute hand 30 of the clock. According to the present improvements there is in addition sleeved between the hour hand shaft 16 and the bearing post 15 an extra or signal impelling hollow shaft 33 which is rotatable independently both of shaft 16 and spindle 17. Signal shaft 33 rotates at the same angular speed at which the wiping contact element 29 travels, namely one revolution in twenty-four hours. Trains of gears, comprising clock work by which the hereinbefore described parts 29, 16, 17 and 33 are rotated simultaneously and in proper synchronism, are described in fuller detail hereinafter.

The function of the extra or signal shaft 33 is to carry and impel in front of clock dial 34 in close face-to-face concealing relation thereto a signal affording rotor or blind 32 which therefore performs one cycle of revolution ever 24 hours. In cooperation with an orbit of insignia in the form of segments 74, 75 of contrasting colors on the central surface of stationary clock face 34 each of half circular extent, and/or suitable markings on the aforesaid 24-hour scale to distinguish time-of-day from time-of-night such as indicia 68 at which a pointer 32' on the rotating signal disc 32 is aimed or radially beamed, the rotor 32 comprises means to signal, substantially throughout each of its successive half-cycles of revolution, indications of respectively differing and distinguishable character each of which indications persists throughout one of the alternate half-cycles of revolution of the rotor.

The area of the front face of the clock dial 34 that is directly back of rotor 32 is colored white in its upper half-circular segment 74 and is colored black in the lower half-circular segment 75. Rotor 32 contains a small aperture 32' that of less than ninety degrees circular extent sweeps around progressively in front of such alternating white and black segments. Thus regardless of whether aperture 32' does or does not have a pointed shape beamed at the 24-hour scale 62 an indication will be signalled that the clock is telling time-of-day whenever white is visible through the aperture 32' or that the clock is telling time-of-night whenever black is visible

through the aperture. Rotor 32 is so synchronized with the wiper contact 29 that a radial line bisecting aperture 32', or whatever pointing device may take its place, coincides with the rotary position of the current making and breaking tip end of said contact. Such synchronized relation, when once established, will be maintained permanently because both the rotor 32 and contact 29 are driven at the same rotary speed. In the absence of aperture 32' some other pointed symbol on rotor 32, or some rotating element such as an extra clock hand, may be rotated by signal shaft 33 to serve as a pointer beamed radially outward from the axis of revolution of the clock hands. This will give equivalent indication by which it can be known that the hour hand 31 of the clock is running on its time-of-day cycle if such symbol points at any part of the upper or white half of the circular extent of the 24-hour scale 62, or that the hour hand of the clock is running on its time-of-night cycle if the symbol points at any part of the lower or black half of the circular extent of the 24-hour scale.

Suitable trains of gears for transmitting drive from a one-revolution-per-hour power pinion 1 of an electric clock motor 63 to hour hand 31, minute hand 30 and the signal rotor 32 simultaneously are as follows. Motor pinion 1 may have 15 teeth of 48 pitch and be in mesh with gear 2 having 60 teeth of 48 pitch. Gear 2 is loose on a countershaft 18 that is journaled in intermediate frame plate 21 at its front end and in the insulative motor frame plate 76 at its rear end. Fast on countershaft 18 is a pinion 5 having 19 teeth of 48 pitch fixed to a gear 3 having 60 teeth of 48 pitch. A yieldable drive, to permit slippage for setting the clock hands in correct time telling position, is transmitted from loose gear 2 to fixed gear 3 in usual manner by means of an axially expansive, cupped, spring washer 57 bearing frictionally between gears 2 and 3. Gear 3 is in mesh with the minute hand spindle pinion 4 having, as does the motor pinion 1, teeth of 48 pitch. Pinion 5 is in mesh with the hour hand spindle gear 6 having 57 teeth of 48 pitch. A pinion 22 is also fixed on counter-shaft 18 and has 9 teeth of 40 pitch and is in mesh with the signal shaft gear 19 having 54 teeth of 40 pitch located just at the rear of intermediate plate 21. It has been mentioned that a similar pinion 7 located at the front of plate 21 having 9 teeth of 40 pitch is in mesh with the wiper contact driving gear 8 having 54 teeth of 40 pitch.

The mat ring 62 is lodged by means of its peripheral edge in a bezel 36 which in turn may be lodged in the sight aperture of a housing 25 of insulative material on which the front frame plate 20, together with intermediate frame plate 21 and the motor carrying frame plate 76, are removably mounted by means of plate spacing posts 23 and 24 and screws 77. The peripheral margin of a dished transparent crystal 78 is held between the mat ring 62 and bezel 36.

It has been mentioned that spring washer 57 permits slippage between power driven gear 2 which is loose on countershaft 18 and gear 3 which is fixed on countershaft 18 in order to permit manual setting to proper time of day or night of all the clockwork impelled parts hereinbefore referred to including contact finger 29, signal rotor 32, hour hand 31 and minute hand 30. Such setting is accomplished by an idler pinion 9 fast on clock setting spindle 54 which has rotary bearing in frame plates 20 and 21 and is provided with a handle knob 54' accessible at the front of housing 25. A back setting limitation click 79 is pivotally mounted on frame plate 21 and engages a ratchet wheel 80 that is fast on spindle 54.

In Fig. 12 terminals of an electric load circuit to be alternately made and broken automatically by the clock-work impelled rotary travel of the resilient leaf element 29 in wiping contact with the respectively conductive and insulative rear surfaces of indicator discs 27 and 26 are represented by two lead wires 81 and 82. Load lead 81 is attached to an insulated binding post 49 mounted on

the insulative motor frame plate 76 and which holds fixed on the latter the conductive resilient leaf collector brush 48 which bears constantly and conductively on the conductive full-circular mounting band 73 from which branches the traveling leaf contact element 29. The other load lead 82 is attached to a bus bar 53 that is tightly lodged under and in electrical contact with the flange of the main bearing post 15 that abuts the front face of the insulative intermediate frame plate 21.

Thus the conductive circuit from lead 82 to lead 81, when the clock controlled switch is closed, can be traced as follows: 82, 53, 15, 69, 27, 29, 73, 48, 49, 81. As long as the tip of traveling contact 29 is separated from conductive disc 27 by the intervention of insulative disc 26, the circuit from lead 82 to lead 81 remains broken.

An example of practical use of my improved time telling instrument is for successively turning on and turning off the current to a radio receiver automatically at predetermined times, such as at a time of day for awakening in the morning and later at a time of night for silencing the radio after having gone to sleep. In Fig. 1 the hands of the clock show the currently existing time to be 3:50. It is known to be 3:50 in the afternoon both because the aperture 32' exposes a portion of the white segment 74 therethrough and also because the tapering or elongated shape of aperture 32' points to the white half of the 24-hour scale 62. In Fig. 2 twelve hours have elapsed and the clock hands 31, 30 are again in the same position indicating the time to be 3:50. Now however the time is known to be 3:50 a.m. at night because the aperture 32' exposes therethrough a portion of the black segment 75 and also because the aperture points to the blackened half of the 24-hour scale 62. In each of Figs. 1 and 2, the red color of indicator disc 26 is set to extend from 7:00 a.m. to midnight on the 24-hour dial 62, and the white of indicator disc 27 extends from midnight to 7:00 a.m. on the same dial. Thus during each full day portion and night portion of a twenty-four hour period the load circuit, comprising say a radio receiving set fed by leads 81, 82 (Fig. 12), will remain energized from 7:00 a.m. to midnight and will remain deenergized from midnight to 7:00 a.m. To perform repeatedly and automatically in this manner requires no daily resetting of any of the controls of the clock or time switch because the colored indicating discs 26, 27 constantly remain wherever they are selectively stationed such as in their relative and absolute positions shown in Figs. 1 and 2.

In Figs. 3 and 4 the color bands 26, 27 have been reset to different relative and absolute arcuate positions on the circle by which it is known that the load current will be energized from 4:00 p.m. (in the afternoon) to 7:00 p.m. (in the evening) and thereafter will be de-energized from 7:00 p.m. (in the evening) to 4:00 p.m. (in the afternoon). Thus if the electrical load controlled by the time switch is the oven of an electric cooking range and the time of day when setting the instrument is 9:00 a.m. (in the morning), as indicated to be the time of day by the hands of the clock giving attention also to the rotary position of aperture 32' in Fig. 3, then when 4:00 p.m. (in the afternoon) arrives the trailing tip of contact wiper 29, traveling clockwise in radial alignment and in unison with the pointed end of aperture 32', will drop off from the edge of the radial split in the rearwardly presented insulative face of disc 26. This automatically begins the cooking of the meal in the oven of the range even if everybody is absent from home. When 7:00 p.m. (in the evening) arrives, the intended time of serving the evening meal, the range oven will automatically be turned off and the cooking will cease because at that time as shown in Fig. 4 the trailing tip of contact wiper 29 will have just passed the dividing line between the red of indicator disc 26 and the white of indicator disc 27. If nobody is present to open the oven the fully cooked meal will be relieved of heating and will not become overcooked.

In Fig. 5, the color bands 26, 27 are shown to be so relatively stationed circumferentially that no red color appears in the annular space between the clock face 24 and the 24-hour scale 62 which space therefore is completely white. In other words no color of red shows at the widthless radial split 51 in disc 27. This means that the trailing tip of contact wiper 29 is constantly traversing always an insulative path along the rear insulative surface of disc 26 wherefore the load circuit will remain always deenergized and will not at anytime be closed automatically by continuous running of the clock. In Fig. 5 the clock hands 30, 31 when viewed in conjunction with the rotary position of aperture 32', tell that the time of day currently is 6:00 p.m.

In Fig. 6, the color bands are so relatively stationed that no white color appears in the annular space between clock face 24 and the 24-hour scale 62 which space therefore is completely red. In other words no color of white shows at the widthless radial split 50 in disc 26. This means that the trailing tip of contact wiper 29 is constantly traversing always a conductive path along the rear conductive surface of disc 27 wherefore the load circuit will remain always closed and will not at any time be opened automatically by the continuous running of the clock whose hands 30, 31 in Fig. 6, in conjunction with the rotary position of aperture 32', tell that the present time is 6:00 a.m.

In the modified construction of Fig. 14 the hour graduations 45' are shown to be carried in a circumferentially outermost position by the mat 62 instead of by dial 34', and the scale of 24-hour time indicia 68' is carried on the innermost dial 34'. This reversed arrangement of markings enables the hour graduations 45' to be located, if preferred, on or circumferentially outside of and round about the crystal 78, or on or circumferentially outside of and round about the crystal retaining bezel 36, as for instance on the front face of casing 25 or some equivalent housing structure.

In Fig. 7a, a mechanical modification is shown wherein the black and white signal segments 75, 74 are centered at the axis of the clock hands and carried on the front face of the signal rotor 32a instead of being stationary. Thus they revolve clockwise just at the rear of a stationary mask or blind 85 that covers and conceals these segments and is fastened to stationary dial 34 or 34' by rivets 86 or in other suitable ways. The mask or blind 85 contains a stationary aperture 85' which may be like aperture 32' through which is exhibited the black of the here traveling segment 75 whenever any portion of same is visible through aperture 85' and exhibits the white of the here traveling segment 74 whenever any portion of the latter is visible through aperture 85'. These traveling black and white segments 75 and 74 in Fig. 7a are arranged in such rotary relation to the hands of the clock 30, 31 and travel in such synchronism with the trailing tip end of wiping contact 29 in relation to the stationed position of aperture 85' that black is exhibited through said aperture throughout the period of time from 6:00 p.m. to 6:00 a.m., and white is exhibited through the aperture from 6:00 a.m. to 6:00 p.m., it being understood that rotor 32a travels continually clockwise at the rate of one revolution in twenty-four hours. If desired, the mask or blind 85 may be made of transparent or translucent material with markings thereon to take the place of aperture 85'.

The foregoing and many other variations and equivalents of the shapes and arrangement of parts herein chosen to illustrate the improvements come within the principles of the invention intended to be covered by the following claims:

I claim:

1. In a settable time switch, the combination of, clock work, a circular scale of time designating indicia, a split disc bordering on said scale having on its rear face a circular conductive switch track and on its front face a

corresponding circular extent of distinctive color, a co-operative split disc bordering on said scale having on its rear face an insulative switch track and on its front face a corresponding circular extent of contrasting color, each of said discs overlapping and extending through a split portion of the other disc and being mounted to be turnable relatively to said other disc and relatively to said scale of indicia in indicating register therewith, at least one of said discs being opaque, means to turn said discs and station them individually in selective positions in circular register with said scale of indicia, a traveling contact at the rear of said discs concealed by said opaque disc and connected to be driven by said clockwork in a circular path in constant wiping engagement sequentially with said tracks, a load circuit connected to be controlled by the cooperation of said contact with said tracks in such manner that said circuit is closed or opened upon the passage of said contact from one to the other of said tracks past the split in one or the other of said overlapping discs, and a signal giving rotor at the front of said disc including an element connected to be driven by said clockwork to sweep along said circular extents of contrasting colors in synchronism with the travel of said concealed contact in a manner to indicate when said contact passes the splits in said discs and shifts from contact with one of said tracks into contact with the other track whereby to make and break the load circuit.

2. In a settable time switch the combination defined in claim 1 in which the said signal giving rotor is one of mutually registering elements having constantly changing circular relationship, one of said elements being connected to be impelled in a circle by said clockwork, and one of said elements bearing night and day distinguishing insignia extending serially about said circle, said day distinguishing insignia extending continuously throughout substantially a half portion of said circle and said night distinguishing insignia extending continuously throughout substantially the remaining half portion of said circle.

3. In a settable time switch, the combination defined in claim 2, in which the one of the said elements which carries the said insignia is stationary and the other of said elements revolves in the said circle.

4. In a settable time switch, the combination defined in claim 2, in which the one of the said elements which carries the said insignia revolves in the said circle and the other of said elements is stationary.

5. In a settable time switch, the combination defined in claim 2, in which the said element which does not carry the said insignia overlaps the said element which does carry the said insignia and is shaped and disposed relatively thereto progressively to mask and expose sequential portions of said insignia.

6. In a settable time switch, the combination defined in claim 5, in which the said element which does not carry the said insignia is operatively opaque and contains a sight aperture located in the said circle in front of the said insignia thereby to limit to a restricted area the portion of said insignia that is visible through said aperture.

7. In a settable time switch, the combination defined in claim 6, in which the said aperture is elongated radially outward toward the said circle to function as a pointer.

8. In a chronometer, a clock driven time telling hand rotatable about an axis, signal devices for distinguishing time of day from time of night, including the combination of cooperative elements including a circular orbit of insignia centered at said axis in part comprising a surface of half circular extent presenting a distinctive signalling appearance, and a blind in front of said orbit of insignia in sufficiently close face-to-face relation thereto to conceal said insignia, said blind having an aperture at a radial distance from said axis to register with said orbit and of less than ninety degrees circular extent, means to cause one of said elements to revolve about

said axis at the speed of one revolution in twenty-four hours while the other element remains stationary, whereby said surface will be exhibited through said aperture continually for at least twelve hours to signal the incidence of day time or night time.

9. In a chronometer, signal devices as defined in claim 8, in which the said half circular surface revolves and the said blind is stationary.

10. In a chronometer, signal devices for distinguishing time of day from time of night, including the combination of, cooperative elements including a circular orbit of insignia in part comprising a stationary surface of half circular extent presenting a distinctive signalling appearance, and a blind supported to revolve in front of said orbit of insignia in sufficiently close face-to-face relation thereto to conceal most of said insignia, said blind having an aperture radially in register with said orbit and of less than ninety degrees circular extent, means to cause said blind to revolve at the speed of one revolution in twenty-four hours while said insignia remain stationary, whereby said surface will be exhibited through said aperture continually for at least twelve hours to signal the incidence of day time or night time.

11. In a chronometer, signal devices as defined in claim 10, together with a stationary scale of time graduations surrounding the said orbit, the said aperture being of pointed shape and so disposed in said blind that the point of said shape aims outward from said orbit toward said time scale whereby progressively to indicate different time graduations in said scale.
